UNITED STATES PATENT OFFICE.

GEORGE SAMUEL BAKER, OF LONDON, ENGLAND.

CONVEYER APPARATUS.

SPECIFICATION forming part of Letters Patent No. 694,519, dated March 4, 1902.

Application filed December 3, 1901. Serial No. 84,568. (No model.)

To all whom it may concern:

Be it known that I, GEORGE SAMUEL BAKER, a subject of the King of England, residing in London, England, have invented certain new and useful Improvements in or Relating to Conveyer Apparatus, (for which I have made application for Letters Patent in Great Britain under No. 22,656, dated November 9, 1901,) of which the following is a specification.

This invention relates to conveyer apparatus adapted for use in a cooling, drying, heating, or the like chamber, and has for its object to provide means by which articles may be introduced into and withdrawn from the chamber without exposing the interior of the latter to the external atmosphere.

According to one method of carrying out this invention the cooling or other chamber is provided with two mouths, one of which serves as a charging-mouth and the other a discharging-mouth. The articles to be treated within the chamber are made to enter by the charging-mouth and after having been exposed to a cooling or other agent within the chamber are withdrawn by the discharging-mouth. A series of receptacles are provided to receive the articles to be treated, and each receptacle is so shaped that it forms with the mouth through which it is passing a valve, so that each mouth is closed in turn by the same receptacle. The mouths of the chamber are conveniently placed one above the other, and an elevator is arranged at the rear end within the chamber to receive the receptacles from the level at which they enter the chamber and lower them to the level of the discharging-mouth if the latter is placed at the bottom. A similar elevator is provided outside the mouths and co-operates with the elevator within the chamber. This second elevator receives the receptacles as they are discharged from the chamber and raises them to the level of the charging-mouth, by which they re-enter the chamber. Each of the receptacles is provided with coupling-tongues at each end, so that as each receptacle is raised or lowered from one level to the other it is automatically disconnected from its adjacent receptacle and connected to the end receptacle on the other level. The receptacles by means of this system of coupling are

made to form their own chain, so that a separate conveyer-band or traveling chain is dispensed with.

Mechanism is provided for operating the elevators at the proper moment and also for advancing and withdrawing the receptacles in their proper order.

In the accompanying drawings, Figure 1 is a longitudinal vertical section of a chamber provided with conveying apparatus constructed according to this invention. Fig. 2 is a plan of the same. Fig. 3 is a side elevation, on an enlarged scale, of the front elevator with its operating mechanism. Fig. 4 is an end elevation of the front elevator, in part section, on line 4-4 of Fig. 3. Fig. 5 is a perspective view of a detail of the conveying apparatus, and Fig. 6 is a longitudinal vertical section of a chamber provided with a modified construction of conveying apparatus.

Like letters indicate like parts throughout the drawings.

The chamber A, Figs. 1 and 2, may be of any convenient construction and is provided with a charging-mouth A' and a discharging-mouth A'', situated vertically one above the other. The receptacles B are each made to exactly fill and completely close the mouths of the chamber as they pass through them and are preferably constructed in the form of oblong frames, open at the top and bottom, adapted to receive trays to support the articles to be treated in the chamber.

Within the chamber A is a platform B', which supports the receptacles as they enter by the charging-mouth, and below this is a second platform or the floor of the chamber B'', upon which the receptacles travel as they return to the discharging-mouth. The platforms B' B'' in the case illustrated comprise rails carried by supports B³, and the receptacles are provided with flanged wheels B⁴, Fig. 4, by which they run upon and are guided by the rails. The wheels B⁴ are recessed in the walls of the receptacles, as clearly shown in the figure referred to, in which part of the receptacle is broken away, so that the wheel on the left-hand side is shown resting upon the rail. The wheel is supported by a pin or screw B⁵ passed through the wall of the receptacle and carried by a plate B⁶ on the inner side.

100

At the end of the platform B' is an elevator C, adapted to rise and fall in guides C', formed in a frame C². The elevator C is conveniently made in the form of a rail-section, 5 so that its rails register with the rails B' when in the raised position and with the rails B² when in the lowered position. Lugs C³ are provided on either side of the elevator, engaging the guides C', and to these lugs are 10 pivoted links D, the free ends of which are in turn pivoted to arms D', secured to rock-shafts D², mounted in the frame C². To each of the rock-shafts D² and preferably midway of the length of each shaft is secured an arm D³, each of which is connected to a rod D⁴, which extends through the whole length of the chamber to mechanism without the same by which the elevator is operated. The receptacles B are received on the rails B² 20 from the elevator C and discharged from the discharging-mouth A² of the chamber onto a stationary platform E. This stationary platform or rail-section is supported by or made integral with a frame E', which also carries the mechanism for operating the elevator C. This mechanism comprises a driving-shaft F, Figs. 3 and 4, which carries a double-toothed quadrant F'. Pivoted at F² to the frame and adapted to gear with the toothed quadrant F' is a wheel F³, carrying a crank-pin F⁴. Mounted transversely in the frame E' is a rock-shaft G, operatively connected by means of an arm G' and a link G² to the crank-pin F⁴ of the toothed wheel F³. 25 A second arm G³ is secured to the rock-shaft G and its free end pivoted to the longitudinal rod D⁴, operatively connected with the elevator C, as described. The wheel F³ is provided at opposite sides with locking portions F⁵, which project beyond the teeth of the wheel and are adapted to engage corresponding locking portions F⁶ on the toothed quadrant F'. 30 To raise the receptacle from the stationary platform E, spring-pawls H are provided, two on either side of the platform. The pawls H are provided with sliding blocks H', operating in grooves or slots H² in the sides of the frame E'. Pivoted to each of the blocks H' is a link G⁴, the free end of which is pivoted to an arm G⁵. The arms G⁵ of the blocks H' of one pair of pawls are secured to the rock-shaft G, and the arms of the other pair of spring-pawls are secured to a second rock-shaft G⁶, mounted parallel to the rock-shaft G. Secured to the rock-shaft G⁶ is an arm G⁷, corresponding to the arm G³ of the rock-shaft G, and these two arms are connected together by the rod D⁴. 45 Above the stationary platform E and level with the rails B' of the charging-mouth is a spring-controlled rail-section J. The rail-section is made in two independent parts, each carried by a pair of spring-arms J'. The spring-arms are secured to the frame E' and allow the two parts of the rail-section to be forced away from each other as a receptacle

is raised between them by the pawls H. Each part J is provided with an inclined portion J², against which the receptacle strikes as it rises, 70 and each part is cut away at J³ to allow the pawls H to rise flush with the top of the rails. Each rail part is thus divided into three separate portions held together by a vertical bridge-piece J⁴, conveniently cast in one with the rail portions. 75 To advance and withdraw the receptacles B, a pair of double spring-pawls K are provided. The two parts of each double pawl K are oppositely arranged upon a cross-head K', 80 mounted in slots or guides K² in the rails B'. The spring-arms which carry the pawls are of such length that the distance between the two opposed pawl-faces of each double pawl is equal to the length of each receptacle. The two pawl ends nearest the mouths of the chamber are upwardly turned and engage the rear lower ends of the receptacles on the rails B', while the two pawl ends farthest from the mouths of the chamber are downwardly directed, so that they engage the upper portions of the rear ends of the receptacles on the rails B². By this arrangement the pawl ends nearest the mouths of the chamber advance the upper line of receptacles when the cross-head 95 is advanced into the chamber, while the pawl ends farthest from the mouths of the chamber withdraw the receptacles on the rails B² when the movement of the cross-head is reversed. 100

To operate the cross-head, connecting-rods K³, Fig. 2, are provided, one at each end of the cross-head. The rods K³ are carried through the end of the chamber, one on each side of the mouths of the chamber, so that they project above the frame E' on either side of the receptacles B. Mounted in suitable bearings in the frame E' is a third rock-shaft L. Secured at each end of this rock-shaft is an arm L', operatively connected by a link L² to one of the connecting-rods K³. An arm L³ is also secured to the rock-shaft L and connected by a link L⁴ to the crank-pin L⁵ of a toothed wheel L⁶, similarly constructed to the toothed wheel F³. The gear-wheel L⁶ is provided with locking-pieces L', corresponding to the locking-pieces F⁵ of the wheel F³ and also co-operates with the double quadrant F' in the same manner as that wheel. 115

As the receptacles are advanced and withdrawn by the pawls K operating conveniently upon the third or fourth receptacle within the chamber of the upper and lower tiers, it is necessary in order that all the receptacles may be operated that they should be connected together by some coupling device. The form of coupling preferred is illustrated in detail in Fig. 5 and comprises a pair of hooked tongues B⁷ B⁸ on the ends of each receptacle. The tongues B⁸ are bell-mouthed 120 or provided with a wider end space at their upper ends than at their lower ends, so that they will not fail to engage the opposed pair of coupling-tongues (during the operation

of the apparatus, as hereinafter described) should the two receptacles about to engage be slightly out of alignment.

The operation of the conveying apparatus 5 is as follows: Presuming a receptacle to be already in position upon the spring-controlled rail-section J in front of the charging-mouth, as shown in the drawings, Figs. 1 to 4, one portion of the double quadrant F' on the 10 driving-shaft F first engages the wheel L⁶ and by rotating this wheel depresses the arm L³ on the rock-shaft L, so that the arms L', connected to the spring-pawl K, are drawn back, moving the pawls toward the mouths of the 15 chamber. This movement of the pawls causes the pawl ends nearest the mouth of the chamber to spring back and pass along beneath one of the receptacles of the upper tier, while the pawl ends remote from the mouth of the 20 chamber engage the receptacle immediately below them, thus causing the receptacles of the lower tier to be moved the length of one receptacle in the direction of the discharging-mouth. By this movement the receptacle 25 shown in the drawings in the discharging-mouth of the chamber is forced out upon the stationary platform or rails E and another receptacle placed in the discharging-mouth. The teeth of the quadrant F' are now disengaged from the wheel L⁶, and one of the locking portions L⁷ coming against one of the locking portions F⁶ of the quadrant causes the wheel L⁶ to be held stationary, so that the 30 arms L' and their connected pawls K remain 35 in the withdrawn position. The double quadrant F' continuing to rotate now engages by means of its second set of teeth the wheel F⁸. The rotation of this wheel causes the arm G' on the rock-shaft G to be depressed by means of 40 its link G² and the crank-pin F⁴ on the wheel, and the movement thus imparted to the rock-shaft operates the arm G³, connected to the rod D⁴, so that the rod is moved in the direction indicated by the arrow. Pivoted to the rod D⁴ is 45 the arm G' on the rock-shaft G⁶, as described above, so that the movement of this rod will cause the rock-shaft G⁶ to move with the rock-shaft G in the direction indicated by the arrows. This movement of the rock-shafts 50 causes the arms G⁵ to be depressed, so that the spring-pawls H, to which they are attached, are drawn down to their lowest position—that is, until the tops of the pawls are brought beneath the level of the rails E. As 55 the pawls descend they spring out on either side of the receptacle upon the rails E as they pass the receptacle and spring in again beneath the receptacle when carried below the rails E. The movement of the rod D⁴ in addition to effecting the operation of the rock-shaft G⁶ operates the elevator C within the chamber. The arms D³ of the rock-shafts D² are pivoted to the rod D⁴, as described above, so that as this rod is moved in the direction 60 indicated by the arrow the arms D' on the rock-shafts D² are raised, carrying with them

the platform C. The quadrant F' now leaves its engagement with the wheel F⁸, so that one of the locking parts F⁵ comes into operation with one of the locking parts F⁶ of the quadrant, and the wheel L⁶ is again operated. This second half-revolution of the wheel L⁶ brings the pawls K back into their original position, so that the pawl ends remote from the mouths of the chamber will now slide 70 over the receptacle beneath them, while the pawl ends nearest the mouth of the chamber engage the receptacle immediately above them and advance the upper tier of receptacles the length of one receptacle. This movement places the end receptacle of the upper tier upon the elevator C and draws the receptacle shown in the drawings upon the spring-controlled rail-section J into the charging-mouth of the chamber. The double quadrant F' now again leaves the wheel L⁶ and operates the wheel F⁸, so that this wheel receives a second half-revolution and replaces the various parts connected with it in the position shown in the drawings. As by this 80 means the pawls H are returned to their raised position, they carry with them the receptacle which formerly rested upon the rails E, and as the latter rises it comes into contact with the inclined portions J² of the rail-sections J, so that the parts J are forced back against the action of the spring-arms J' and allow the passage of the receptacle. As soon as the receptacle is raised free of the spring-controlled rail-section J the two rail portions 85 90 spring in beneath the receptacle and serve to support it as it is drawn into the chamber. In raising the receptacle from the rails E to the rails J the coupling-tongues B⁸ are made to slide vertically out of their engagement 95 with the tongues B⁷ of the adjacent receptacle and engage tongues B⁷ of the receptacle in the charging-mouth. Simultaneous with the upward movement of the pawls H the elevator C is lowered by the reverse movement of 100 the rod D⁴, so that the receptacle resting upon it is brought into alignment with the discharging-mouth of the chamber, being disconnected from the end receptacle on the rails E' and connected with the end receptacle on the rails 105 110 B² by means of the coupling devices, as described with reference to the receptacle outside the chamber. This completes one series 115 of operations, which may be continuously repeated.

It will be observed that the automatic connecting and disconnecting of the receptacles by means of the coupling-tongues B⁷ B⁸ enables an elevator band or chain to be dispensed with, the receptacles themselves forming the chain, so that either the upper or the lower tier may be moved as one body.

Clutch mechanism of any convenient construction may be provided, so that the quadrant F' may be prevented from rotating whenever desired, this being especially useful 125 where two or more cooling-chambers may be

arranged side by side and provided with apparatus of the kind described operated by a compound mechanism.

In Fig. 6 a modified construction of apparatus is illustrated, in which the spring-pawl H and spring-controlled rail-section J are dispensed with. In place of the spring-pawl H a platform or rail-section M is provided similar to the platform C in the interior of the chamber, and the links G⁴, formerly connected to the sliding blocks H' of the spring-pawl H, are connected to lugs M' on the sides of the platform, sliding in slots or guides M² in the frame E'. It will be noted also that the position of the levers D' D³ of the elevator C is reversed, so that the elevator is now raised by moving the rod D⁴ to the right instead of by a movement to the left, as before. This construction allows both elevators to rise and fall simultaneously. The operation of this apparatus is as follows: Presuming both elevators to be raised, as shown in the figure, and a receptacle resting upon the elevator outside the chamber, the double-toothed quadrant F' first engages the wheel L⁶, so that the spring-pawl K are advanced into the chamber, carrying with them the upper tier of receptacles. This places a receptacle upon the elevator C and that upon the elevator M is drawn into the charging-mouth of the chamber. The quadrant F' now frees the wheel L⁶ and engages the wheel F³, so that the elevator M is lowered, and with it the elevator C within the chamber. The elevator M thus comes into position to receive a receptacle from the discharging-mouth, and the elevator C moves the end receptacle of the upper tier from alinement with the charging-mouth and connects it to the lower tier in alinement with the discharging-mouth. The continued movement of the double quadrant F' now frees the wheel F³ and again operates the wheel L⁶, so that the pawls K are moved toward the mouths of the chamber, carrying with them the lower tier of receptacles and discharging the receptacle shown in the discharging-mouth onto the elevator M. The quadrant F' now frees the wheel L⁶ and engages the wheel F³, so that both elevators M and C are again raised and the parts restored to the first position, as shown in the drawings.

It is found convenient to make the walls of the mouths of the chamber extend the full length of each receptacle, and for this purpose inwardly-directed extensions A³ are formed on the end wall of the chamber, thus constituting a conduit which the receptacles fit. Obviously these extensions may be dispensed with by making the wall the thickness required, and this thickness may be reduced by shortening the receptacles.

The cooling apparatus employed may be of any convenient construction, that shown in the drawings comprising a pipe N, arranged above the receptacles for circulating the cooling agent. Vertically beneath the pipe is disposed a tray or gutter N', depressed at one

end from the horizontal line, so that moisture condensing upon the pipe N may drip into the gutter and flow to the lower end, where it is carried off by a waste-pipe N², communicating with a gutter N³ in the floor of the chamber. The gutter N³ is conveniently used for the reception of the connecting-rod D⁴. Communicating with the gutter is a trapped pipe N⁴, of known construction, by which the liquid as it collects may be carried off from the chamber. In addition to the circulating-pipes N or in place of these brine-tanks may be used, if desired.

Obviously mechanisms other than that described may be used to operate the receptacles whether required to operate as described with reference to Figs. 1 to 4 or Fig. 6, any mechanism being suitable for this purpose which will give the required order of rotation to the receptacles.

What I claim as my invention, and desire to secure by Letters Patent, is—

1. In conveying apparatus for a cooling or other chamber the combination of a chamber, a charging-mouth to the chamber, a discharging-mouth to the chamber, a series of receptacles adapted to pass through the charging and discharging mouths, means whereby each receptacle forms with the mouth through which it is passing a valve so that each mouth in turn is closed by the same receptacle, means for advancing the receptacles into the chamber through the charging-mouth, means for supporting the receptacles within the chamber and means for withdrawing the receptacles from the chamber by the discharging-mouth as set forth.

2. In a conveying apparatus for a cooling or other chamber the combination of a chamber, a charging-mouth at one end of the chamber, a discharging-mouth at the same end, a series of receptacles adapted to pass through the charging and discharging mouths of the chamber, means whereby each receptacle forms with the mouth through which it is passing a valve so that each mouth in turn is closed by the same receptacle, means for advancing the receptacles into the chamber through the charging-mouth, means for supporting the receptacles within the chamber, means for withdrawing the end receptacle within the chamber from its alinement with the charging-mouth and placing it in alinement with the discharging-mouth and means for withdrawing the receptacles from the chamber by the discharging-mouth as set forth.

3. In a conveying apparatus for a cooling or other chamber the combination of a chamber, a charging-mouth at one end of the chamber, a discharging-mouth at the same end, a series of receptacles adapted to pass through the charging and discharging mouths of the chamber, means whereby each receptacle forms with the mouth through which it is passing a valve so that each mouth in turn is closed by the same receptacle, means for

advancing the receptacles into the chamber through the charging-mouth, means for supporting the receptacles within the chamber, means for withdrawing the end receptacle 5 within the chamber from its alinement with the charging-mouth and placing it in alinement with the discharging-mouth, means for withdrawing the receptacles from the chamber by the discharging-mouth and means for 10 placing the discharged receptacles in position to reenter the charging-mouth as set forth.

4. In a conveying apparatus for a cooling or other chamber the combination of a chamber, a charging-mouth at one end of the chamber, a discharging-mouth at the same end, a 15 series of receptacles adapted to pass through the charging and discharging mouths of the chamber, means whereby each receptacle forms with the mouth through which it is 20 passing a valve so that each mouth in turn is closed by the same receptacle, means for advancing the receptacle into the chamber through the charging-mouth, means for supporting the receptacles within the chamber, 25 means for interlocking the receptacles as they enter the chamber, means for withdrawing the end receptacle within the chamber from its alinement with the charging-mouth and placing it in alinement with the discharging- 30 mouth, means for automatically disconnecting each receptacle within the chamber from the incoming receptacles as it is moved out from alinement with the charging-mouth and for interlocking it with the outgoing receptacles as it is moved into alinement with the 35 discharging-mouth, and means for withdrawing the receptacles from the chamber by the discharging-mouth as set forth.

5. In a conveying apparatus for a cooling or other chamber the combination of a chamber, a charging-mouth at one end of the chamber, a discharging-mouth at the same end, a 40 series of receptacles adapted to pass through the charging and discharging mouths of the chamber, means whereby each receptacle forms with the mouth through which it is passing a valve so that each mouth in turn is closed by the same receptacle, means for advancing the receptacles into the chamber 45 through the charging-mouth, means for supporting the receptacles within the chamber, means for withdrawing the end receptacle within the chamber from its alinement with the charging-mouth and placing it in alinement with the discharging-mouth, means for 50 withdrawing the receptacles from the chamber by the discharging-mouth, means for placing the discharged receptacles in position to reenter the charging-mouth and automatically-operating coupling-tongues on the ends 55 of each receptacle as set forth.

6. In a conveying apparatus for a cooling

or other chamber the combination of a chamber, a charging-mouth at one end of the chamber, a discharging-mouth at the same end, a 70 series of receptacles adapted to pass through the charging and discharging mouths of the chamber, means whereby each receptacle forms with the mouth through which it is 75 passing a valve so that each mouth in turn is closed by the same receptacle, automatically-operating coupling-tongues on the ends of each receptacle, means for advancing the receptacles into the chamber through the charging-mouth, means for supporting the receptacles within the chamber, means for withdrawing the end receptacle within the chamber from its alinement with the charging-mouth and placing it in alinement with the discharging-mouth and means for withdrawing the receptacles from the chamber by the discharging-mouth as set forth.

7. In a conveying apparatus for a cooling or other chamber the combination of a chamber, a charging-mouth at one end of the chamber, a discharging-mouth at the same end, a 80 series of receptacles adapted to pass through the charging and discharging mouths of the chamber, means whereby each receptacle 85 forms with the mouth through which it is passing a valve so that each mouth in turn is closed by the same receptacle, means for advancing the receptacles into the chamber through the charging-mouth, means for supporting the receptacles within the chamber, means for withdrawing the end receptacle within the chamber from its alinement with the charging-mouth and placing it in alinement with the discharging-mouth, means for 90 withdrawing the receptacles from the chamber by the discharging-mouth, means for placing the discharged receptacles in position to reenter the charging-mouth and automatically-operating coupling-tongues on the ends 95 of each receptacle as set forth.

8. In a conveying apparatus for a cooling or other chamber the combination of a chamber, a charging-mouth at one end of the chamber, a discharging-mouth at the same end, a 100 series of receptacles adapted to pass through the charging and discharging mouths of the chamber, means whereby each receptacle forms with the mouth through which it is passing a valve so that each mouth in turn is closed by the same receptacle, automatically-operating bell-mouthed coupling-tongues 105 on the ends of each receptacle, means for advancing the receptacles into the chamber through the charging-mouth, means for supporting the receptacles within the chamber, means for withdrawing the end receptacle within the chamber from its alinement with the charging-mouth and placing it in alinement with the discharging-mouth and means 110 for withdrawing the receptacles from the chamber by the discharging-mouth as set forth.

9. In a conveying apparatus for a cooling

or other chamber the combination of a chamber, a charging-mouth at one end of the chamber, a discharging-mouth at the same end, a series of receptacles adapted to pass through 5 the charging and discharging mouths of the chamber, means whereby each receptacle forms with the mouth through which it is passing a valve so that each mouth in turn is closed by the same receptacle, means for advancing the receptacles into the chamber through the charging-mouth, means for supporting the receptacles within the chamber, means for withdrawing the end receptacle within the chamber from its alinement with 10 the charging-mouth and placing it in alinement with the discharging-mouth, means for withdrawing the receptacles from the chamber by the discharging-mouth, means for placing the discharged receptacles in position to reenter the charging-mouth, and automatically-operating bell-mouthed coupling-tongues on the ends of each receptacle as set forth.

10. In conveying apparatus for a cooling or other chamber the combination of a chamber, 25 a charging-mouth at one end of the chamber, a platform within the chamber level with the charging-mouth, a discharging-mouth at the same end as and below the charging-mouth, a series of receptacles adapted to pass through 30 the charging and discharging mouths of the chamber, means whereby each receptacle forms with the mouth through which it is passing a valve so that each mouth in turn is closed by the same receptacle, means within 35 the chamber for receiving the receptacles at the end of the charging-mouth platform and delivering them upon the floor of the chamber in alinement with the discharging-mouth, guides within the chamber, a cross-head 40 mounted in these guides between the advance and return tiers of receptacles, a forwardly-operating pawl on the cross-head adapted to engage the upper tier of receptacles, a rearwardly-operating pawl secured to the cross-head and adapted to engage the lower tier of 45 receptacles and means for reciprocating the cross-head as set forth.

11. In conveying apparatus for a cooling or other chamber the combination of a chamber, 50 a charging-mouth at one end of the chamber, a platform within the chamber level with the charging-mouth, a discharging-mouth at the same end as and below the charging-mouth, a series of receptacles adapted to pass through 55 the charging and discharging mouths of the chamber, means whereby each receptacle forms with the mouth through which it is passing a valve so that each mouth in turn is closed by the same receptacle, guides within 60 the chamber for the receptacles, means for advancing the receptacles through the charging-mouth into the chamber, an elevator within the chamber at the end of the charging-mouth platform, mechanism for alternately raising the elevator to the platform within the chamber and lowering it to the 65

floor of the latter, a driving-shaft, a frame to carry the driving-shaft, a toothed quadrant secured to the driving-shaft, a toothed wheel pivoted to the frame and adapted to be engaged by the quadrant, mechanism operatively connecting the toothed wheel with the mechanism of the elevator, means for locking the toothed wheel when not engaged by the quadrant and means for withdrawing the receptacles from the discharging-mouth of the chamber as set forth.

12. In conveying apparatus for a cooling or other chamber the combination of a chamber, 80 a charging-mouth at one end of the chamber, a platform within the chamber level with the charging-mouth, a discharging-mouth at the same end as and below the charging-mouth, a series of receptacles adapted to pass through 85 the charging and discharging mouths of the chamber, means whereby each receptacle forms with the mouth through which it is passing a valve so that each mouth in turn is closed by the said receptacle, guides within the chamber for the receptacles, means for advancing the receptacles through the charging-mouth into the chamber, an elevator within the chamber at the end of the charging-mouth platform, mechanism for alternately raising 90 the elevator to the platform within the chamber and lowering it to the floor of the latter, a driving-shaft a frame to carry the driving-shaft, a toothed quadrant secured to the driving-shaft, a toothed wheel pivoted to the frame and adapted to be engaged by the quadrant, mechanism operatively connecting the toothed wheel with the mechanism of the elevator, locking portions formed on the toothed wheel at opposite points, a locking portion on 95 the quadrant co-operating with those on the toothed wheel, and means for withdrawing the receptacles from the discharging-mouth of the chamber as set forth.

13. In conveying apparatus for a cooling or other chamber the combination of a chamber, 110 a charging-mouth at one end of the chamber, a platform within the chamber level with the charging-mouth, a discharging-mouth at the same end as and below the charging-mouth, 115 a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, 120 a forwardly-operating spring-pawl secured to the cross-head and adapted to engage the receptacles on the platform within the chamber, a connecting-rod secured at each end of the cross-head and extending through the front wall of the chamber on either side of the receptacles, a frame outside the mouths of the chamber, a toothed wheel pivoted to the frame, a crank-pin on the wheel, mech-

- anism operatively connecting the crank-pin with the connecting-rods of the cross-head for reciprocating the latter, a driving-shaft, a toothed quadrant secured to the driving-shaft and adapted to engage the teeth of the wheel, means for automatically locking the wheel when not engaged by the quadrant, an elevator within the chamber at the end of the platform, mechanism for alternately raising the elevator to the platform within the chamber and lowering it to the floor of the latter, a second toothed wheel pivoted to the frame and adapted to coöperate with the quadrant, an operating-rod connecting the mechanism of this elevator with this toothed wheel, and a rear operating spring-pawl secured to the cross-head of the forwardly-operating pawl and adapted to engage the receptacles on the floor of the chamber as set forth.
14. In conveying apparatus for a cooling or other chamber the combination of a chamber, a charging-mouth at one end of the chamber, a platform within the chamber level with the charging-mouth, a discharging-mouth at the same end as and below the charging-mouth, a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a frame, a toothed wheel pivoted to the frame, a crank-pin on the wheel, mechanism operatively connecting the crank-pin with the cross-head for reciprocating the latter, a driving-shaft, a toothed quadrant secured to the driving-shaft and adapted to engage the teeth of the wheel, means for automatically locking the wheel when not engaged by the quadrant, an elevator within the chamber at the end of the platform, mechanism for alternately raising the elevator to the platform within the chamber and lowering it to the floor of the latter, a second toothed wheel pivoted to the frame and adapted to coöperate with the quadrant, an operating-rod connecting the mechanism of this elevator with this toothed wheel, and a rear operating spring-pawl secured to the cross-head of the forwardly-operating pawl and adapted to engage the receptacles on the floor of the chamber as set forth.
15. In conveying apparatus for a cooling or other chamber the combination of a chamber, a charging-mouth at one end of the chamber, a platform in the chamber level with the charging-mouth, a discharging-mouth at the same end as and below the charging-mouth, a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a frame, a toothed wheel pivoted to the frame, a crank-pin on the wheel, mechanism operatively connecting the crank-pin with the cross-head for reciprocating the latter, a driving-shaft, a toothed quadrant secured to the driving-shaft and adapted to engage the teeth of the wheel, means for automatically locking the wheel when not engaged by the quadrant, an elevator within the chamber at the end of the platform, mechanism for alternately raising the elevator to the platform within the chamber and lowering it to the floor of the latter, a second toothed wheel pivoted to the frame and adapted to coöperate with the quadrant, an operating-rod connecting the mechanism of this elevator with this toothed wheel, and a rear operating spring-pawl secured to the cross-head of the forwardly-operating pawl and adapted to engage the receptacles on the floor of the chamber as set forth.
16. In conveying apparatus for a cooling or other chamber the combination of a chamber, a charging-mouth at one end of the chamber, a platform in the chamber level with the charging-mouth, a discharging-mouth at the same end as and below the charging-mouth, a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a frame, a toothed wheel pivoted to the frame, a crank-pin on the wheel, mechanism operatively connecting the crank-pin with the cross-head for reciprocating the latter, locking portions formed on the toothed wheel at opposite points, a driving-shaft, a toothed quadrant secured to the driving-shaft and adapted to engage the teeth of the wheel, a locking portion on the quadrant coöperating with those on the toothed wheel, a second toothed wheel pivoted to the frame and adapted to coöperate with the toothed quadrant on the driving-shaft, an elevator within the chamber at the end of the platform, mechanism for alternately raising the elevator to the platform within the chamber and lowering it to the floor of the latter, a rod operatively connecting the mechanism of this elevator with the second toothed wheel on the external frame and a rearwardly-operating spring-pawl secured to the cross-head of the forwardly-operating pawl and adapted to engage the receptacles on the floor of the chamber as set forth.

- locking portion on the quadrant coöperating with those on the toothed wheel, a second toothed wheel pivoted to the frame and adapted to coöperate with the toothed quadrant
- 5 on the driving-shaft, an elevator within the chamber at the end of the platform, mechanism for alternately raising the elevator to the platform within the chamber and lowering it to the floor of the latter, a rod operatively
- 10 connecting the mechanism of the elevator with the second toothed wheel on the frame and a rearwardly-operating spring-pawl secured to the cross-head of the forwardly-operating pawl and adapted to engage the receptacles on the floor of the chamber as set forth.
- 15 17. In conveying apparatus for a cooling or other chamber the combination of a chamber, a charging-mouth at one end of the chamber, a platform within the chamber level with the charging-mouth, a discharging-mouth at the same end as and below the charging-mouth, an elevator outside the mouth of the chamber, a frame to support the elevator, a toothed
- 20 wheel pivoted to the frame, a crank-pin on the wheel, mechanism operatively connecting the crank-pin and the elevator for raising and lowering the latter, a driving-shaft, a toothed quadrant secured to the driving-shaft and
- 25 adapted to engage the teeth of the wheel, means for automatically locking the wheel when not engaged by the quadrant, a series of receptacles adapted to pass through the charging and discharging mouths of the chamber,
- 30 35 means whereby each receptacle forms with the mouth through which it is passing a valve so that each mouth in turn is closed by the same receptacle, guides within the chamber for the receptacles, means for advancing the receptacles into the chamber, an elevator within the chamber at the end of the platform, mechanism for alternately raising the elevator to the platform within the chamber and lowering it to the floor of the latter, an operating-rod connecting the mechanism of this elevator with the mechanism of the outside elevator and means for withdrawing the receptacles from the discharging-mouth as set forth.
- 40 45 50 55 60 65 18. In conveying apparatus for a cooling or other chamber the combination of a chamber, a charging-mouth at one end of the chamber, a platform within the chamber level with the charging-mouth, a discharging-mouth at the same end as and below the charging-mouth, an elevator outside the mouth of the chamber, a frame to support the elevator, a toothed wheel pivoted to the frame, a crank-pin on the wheel, mechanism operatively connecting the crank-pin and the elevator for raising and lowering the latter, locking portions formed on the toothed wheel at opposite points, a driving-shaft, a toothed quadrant secured to the driving-shaft and adapted to engage the teeth of the wheel, a locking portion on the quadrant coöperating with those on the toothed wheel, a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a connecting-rod secured at each end of the cross-head and extending through the front wall of the chamber on either side of the receptacles, a second toothed wheel pivoted to the frame of the elevator and adapted to coöperate with the toothed quad-

means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a connecting-rod secured at each end of the cross-head and extending through the front wall of the chamber on either side of the receptacles, a second toothed wheel pivoted to the frame of the elevator and adapted to coöperate with the toothed quadrant on the driving-shaft, mechanism operatively connecting this second toothed wheel with the connecting-rods of the cross-head for reciprocating the latter, an elevator within the chamber at the end of the platform, mechanism for alternately raising the elevator to the platform within the chamber and lowering it to the floor of the latter, an operating-rod connecting the mechanism of this elevator with the mechanism of the outside elevator and a rearwardly-operating spring-pawl secured to the cross-head of the forwardly-operating pawl and adapted to engage the receptacles on the floor of the chamber as set forth.

19. In conveying apparatus for a cooling or other chamber the combination of a chamber, a charging-mouth at one end of the chamber, a platform within the chamber level with the charging-mouth, a discharging-mouth at the same end as and below the charging-mouth, an elevator outside the mouth of the chamber, a frame to support the elevator, a toothed wheel pivoted to the frame, a crank-pin on the wheel, mechanism operatively connecting the crank-pin and the elevator for raising and lowering the latter, locking portions formed on the toothed wheel at opposite points, a driving-shaft, a toothed quadrant secured to the driving-shaft and adapted to engage the teeth of the wheel, a locking portion on the quadrant coöperating with those on the toothed wheel, a series of receptacles adapted to pass through the charging and discharging mouths of the chamber, means whereby each receptacle forms with the mouth through which it is passing a valve so that each mouth in turn is closed by the same receptacle, vertically-operating coupling-tongues on the ends of each receptacle, guides within the chamber for the receptacles, other guides within the chamber, a cross-head mounted in these other guides, a forwardly-operating spring-pawl secured to the cross-head and adapted to engage the receptacles on the platform within the chamber, a connecting-rod secured at each end of the cross-head and extending through the front wall of the chamber on either side of the receptacles, a second toothed wheel pivoted to the frame of the elevator and adapted to coöperate with the toothed quad-

rant on the driving-shaft, mechanism operatively connecting this second toothed wheel with the connecting-rods of the cross-head for reciprocating the latter, an elevator within the chamber at the end of the platform, mechanism for alternately raising the elevator to the platform within the chamber and lowering it to the floor of the latter, an operating-rod connecting the mechanism of this elevator with the mechanism of the outside elevator and a rearwardly-operating spring-pawl secured to the cross-head of the forwardly-operating pawl and adapted to engage the receptacles on the floor of the chamber as set forth.

20. In conveying apparatus for a cooling or other chamber the combination of a chamber, a charging-mouth at one end of the chamber, a platform within the chamber flush with the floor of the charging-mouth, a discharging-mouth at the same end and below the charging-mouth, an elevator outside the mouths of the chamber, a frame to support the elevator, vertical slots in the frame, a lug on each side of the elevator engaging the slots in the frame, a shaft supported by the frame and mounted transversely to the chamber, arms secured one at each end of the shaft, links connecting the free end of the arms to the lugs of the elevator, a third arm on the shaft, a toothed wheel pivoted to the frame, a crank-pin on the wheel, a link connecting the crank-pin with the third arm on the shaft, locking portions formed on the toothed wheel at opposite points, a driving-shaft, a toothed quadrant secured to the driving-shaft and adapted to engage the teeth of the wheel, a locking portion on the quadrant coöperating with that on the toothed wheel, a series of receptacles adapted to pass through the charging and discharging mouths of the chamber, means whereby each receptacle forms with the mouth through which it is passing a valve so that each mouth in turn is closed by the same receptacle, vertically - operating coupling-

tongues on the ends of each receptacle, guides within the chamber for the receptacles, other guides within the chamber, a cross-head mounted in these guides, a forwardly-operating spring-pawl secured to the cross-head and adapted to engage the receptacles on the platform within the chamber, a connecting-rod secured at each end of the cross-head and extending through the front wall of the chamber on either side of the receptacles, links on the free ends of the rods outside the chamber, operating-arms pivoted to the links, a shaft mounted in the elevator-frame, means for connecting the operating-arms to this shaft, a third arm secured to this shaft, a toothed wheel pivoted to the frame and adapted to coöperate with the toothed quadrant on the driving-shaft, a crank-pin on this wheel, a link operatively connecting the crank-pin and third arm on the shaft, locking portions on opposite sides of the wheel adapted to coöperate with the locking portion on the toothed quadrant, an elevator within the chamber at the end of the charging-mouth platform, a frame for the elevator, vertical slots in the frame, a lug one on each side of the elevator engaging the slots, a shaft supported by the frame and mounted transversely to the chamber, arms secured one at each end of the shaft, links connecting the free ends of the arms to the lugs of the elevator, a third arm on the shaft, a rod operatively connecting this arm with the corresponding arm of the other elevator and a rearwardly-operating pawl secured to the cross-head of the forwardly-operating pawl and adapted to engage the receptacles on the floor of the chamber as set forth.

In testimony whereof I have signed my name to this specification in the presence of two subscribing witnesses.

GEORGE SAMUEL BAKER.
